UNITED STATES PATENT OFFICE.

OTTO H. LEMCKE, OF NEW YORK, N. Y.

HAT-RETAINING DEVICE.

Application filed February 12, 1923; Serial No. 618,523.

To all whom it may concern:

Be it known that I, OTTO H. LEMCKE, a citizen of the United States, and a resident of the city of New York, borough of Manhattan, in the county and State of New York, have invented a new and Improved Hat-Retaining Device, of which the following is a full, clear, and exact description.

This invention has relation to head wear and has particular reference to a device for retaining a hat, cap or other head wear securely in place on the head to prevent accidental displacement thereof.

The invention contemplates for its primary object the provision of a hat retaining device which affords ready means for detachably associating the device with the hat, cap or head wear and which when in active position operates to securely retain the hat against displacement.

As a further object the invention contemplates means for adjusting the device to the head in order that the same may be applicable to heads of various sizes.

As a still further object the invention provides a hat retaining device which is not readily discernible when in place and which may be readily applied or removed at will.

The invention furthermore contemplates a device of the character described which is extremely simple in its construction, highly efficient in its purpose and which may be manufactured and sold at a minimum price.

With the above recited and other objects in view, the invention resides in the novel construction set forth in the following specification, particularly pointed out in the appended claims and illustrated in the accompanying drawing, it being understood that the right is reserved to embodiments other than those actually illustrated herein, to the full extent indicated by the general meaning of the terms in which the claims are expressed.

In the drawing—

Figure 1 is a perspective view illustrating use and application of the retaining device.

Fig. 2 is a similar view of the device removed from the hat.

Referring to the drawing by characters of reference, A designates a hat provided with the usual sweat band B arranged in the head receiving opening. The device consists of a

member 10 preferably constructed from a strip of fabric which is doubled upon itself and provided with parallel transverse lines of stitching 11 defining a passageway or tunnel 12. A strip of elastic 13 has its opposite free extremities 14 passed through the tunnel or passageway 12 from opposite directions to provide a crossed relation of the ends within the passageway whereby the major portion of the elastic strip is arranged in looped form for encircling the head of the wearer, the said crossed relation of the ends within the passageway serving to set up a sufficient frictional engagement with each other and with the passageway to prevent casual or accidental movement. A bowed resilient element 15 having pads 16 at its opposite ends is positioned with its medial portion in the passageway or tunnel 12.

In use and operation the member 10 is inserted between the sweat band and the crown C of the hat, preferably at the front portion thereof, as illustrated in Fig. 1, with the portion which defines the tunnel or passageway 12 projecting above the sweat band. The resilient bowed element 15 lies within and frictionally engages the sides of the crown as illustrated in Fig. 1, thus associating the device with the hat. The user, when placing the hat upon the head, engages the looped portion of the elastic strip 13 around the back of the head, thus securely holding the hat in fixed relation against accidental displacement. To obtain various adjustments in the diameter of the loop, the ends 14 are manipulated as will be readily understood. When not in use the device may either be left in the hat or removed and placed in the pocket.

If desired the device may be used in the following manner in lieu of engaging the elastic band in looped form about the head. One of the ends 14 after the device is associated with the hat, is pulled outwardly to cause the looped portion of the band to be tightened about the member 10 and the long end is then tied to one of the buttons of the vest or coat, or otherwise attached to an article of clothing.

I claim:

1. A hat retaining device comprising a member engageable between the sweat band and the crown, said member having a pas-

sage or tunnel therethrough, and a strip of elastic having its ends passed through said passage or tunnel from opposite directions whereby the elastic is detachably and adjustably associated with the hat.

2. A hat retaining device comprising a member having a passage or tunnel therethrough, and a strip of elastic having its ends passed through said passage or tunnel from opposite directions to maintain the elastic strip in looped form for encircling the head of the wearer.

3. A hat retaining device comprising a member having a passage or tunnel therethrough, and a strip of elastic having its ends passed through said passage or tunnel from opposite directions to maintain the elastic strip in looped form for encircling the head of the wearer, said member consti-

tuting means for detachably associating the elastic strip with the hat.

4. A hat retaining device comprising a member having a passage or tunnel therethrough, and a strip of elastic having its ends passed through said passage or tunnel from opposite directions to maintain the elastic strip in looped form for encircling the head of the wearer, and a bowed resilient element with its medial portion passing through the tunnel or passage, the opposite ends of said element bearing against the inner sides of the head receiving opening for connecting the device with the hat, the said member being insertable between the sweat band and the crown to further serve as means for preventing displacement of the device.

OTTO H. LEMCKE.
